United States Patent Office

Des. 183,492
Patented Sept. 9, 1958

183,492

PHONOGRAPH

John P. Lotus, Lansing, Mich.

Application December 13, 1957, Serial No. 48,894

Term of patent 14 years

(Cl. D56—4)

Figure 1 is a front perspective view of a phonograph showing my new design;

Figure 2 is a rear perspective view; and

Figure 3 is a side elevational view thereof.

I claim:

The ornamental design for a phonograph, as shown.
